ENGINE STARTER DRIVE

James E. Buxton, Elmira, N. Y., assignor to Bendix Aviation Corporation, South Bend, Ind., a corporation of Delaware

Application December 9, 1941, Serial No. 422,241

2 Claims. (Cl. 74—7)

The present invention relates to an engine starter drive and more particularly to yieldable gearing for connecting a starting motor to an engine member.

In those forms of starter drive in which a pinion is projected by a threaded connection into mesh with an engine gear when the starting motor is accelerated, some form of yielding connection is necessary. The utilization of many forms of rubber-like substances to perform this function by virtue of their elastic resistance to deformation have been proposed, some forms utilizing the elastic substance in compression, some in torsion, and some in both compression and torsion; and each form has been found to have certain advantages and limitations for specific uses.

It is an object of the present invention to provide a novel yielding drive for engine starters which is efficient and reliable in operation and economical in construction.

It is another object to provide such a device which is of large torque capacity in proportion to the volume of its cushioning element.

It is another object to provide such a device in which the yielding connection comprises a rubber-like member which is placed in axial shear when the drive is torqued.

It is a further object to provide such a device incorporating means for relieving the yielding member from the application of torque thereto.

It is another object to provide such a device in which the engagement of the pinion with the engine gear is cushioned and facilitated by the yielding action of the rubber-like member in axial shear.

Further objects and advantages will be apparent from the following description taken in connection with the accompanying drawing, in which:

Fig. 1 is a side elevation partly in section of a starter drive incorporating a preferred embodiment of the present invention;

Fig. 2 is a similar view of a second embodiment of the invention;

Fig. 3 is a detail in perspective of the yielding driving member shown in Fig. 2; and

Fig. 4 is a view similar to Fig. 1 of a third embodiment of the invention.

In Fig. 1 of the drawing there is illustrated a power shaft 1 having a smooth reduced extension 2 providing a thrust shoulder 3. A pinion 4 is slidably journalled on the smooth portion 2 of the shaft for movement into and out of engagement with a member such as a gear 5 of an engine to be started.

The power shaft 1 is provided with a further reduced extension 6 on which a screw shaft 7 is fixed as by means of a pin 8. Screw shaft 7 is provided with a smooth portion 9 and a threaded portion 11 of the same external diameter as the smooth portion 2 of the power shaft.

Means for traversing and rotating the pinion 4 from the screw shaft is provided comprising a nut member 12 normally journalled on the smooth portion 9 of the screw shaft and urged into initial engagement with the threads 11 by means of a re-entry spring 13 which bears at one end against a thimble 14 anchored on the screw shaft by a lock wire 15, and at the other end against a thimble 16 slidably mounted on the screw shaft. A flange 17 on the screw shaft limits the sliding movement of the thimble 16 so as to define the idle position of the nut 12 in initial engagement with the end of the threads 11.

Nut 12 is provided with a radial flange 18 having a splined connection as indicated at 19 with a barrel member 21 fixed to the pinion 4 at 22. A lock ring 23 is provided for retaining the nut 12 within the barrel 21. According to the present invention an elastically deformable annular member 24 is mounted in the barrel 21, seated on the nut 12, and so connected interiorly and exteriorly to the nut and barrel respectively, that relative movement between the nut and barrel places the elastic member in axial shear. As here shown, this is accomplished by bonding sleeves 25 and 26 to the interior and exterior of the annular member 24, the interior sleeve 25 being in 35 abutting relation with the flange 18 of the nut, and the sleeve 26 being seated against a shoulder 27 formed in the interior of the barrel 21. In this form of the invention the member 24 is shown as having a conical or truncated form so arranged that when shearing stresses are applied thereto during the operation of the drive, the member tends to be flattened out.

In the operation of this embodiment of the invention, rotation of the power shaft 1 is transmitted through the pin 8 to the screw shaft 9. The nut 12 is thereby threaded along the screw shaft 9, moving the barrel 21 and pinion 4 ahead of it by means of the yielding member 24 until the pinion 4 meshes the engine gear 5 and engages the abutment shoulder 3. Thereafter further longitudinal movement of the nut 12 places the member 24 in axial shear until the elastic resistance to this shearing movement causes sufficient torque to be transmitted through splined connection 19 between the nut and barrel to cause

rotation of the pinion to crank the engine. When the engine starts, the overrunning of the engine gear returns the parts to idle position.

In the embodiment illustrated in Fig. 2, the arrangement is substantially similar to that shown in Fig. 1 except that the annular elastic member is normally flat, and the axial shearing forces engendered by the transmission of torque deform the member into a truncated shape. The nut 12 is provided with an abutment shoulder 13 for spacing the sleeve 25 from the flange 18 in order to permit this telescoping movement of the parts. In this form also, the step 2 of the power shaft 1 is removed in order to permit the use of a smaller drive pinion 4.

The operation of this embodiment of the invention is substantially the same as above set forth.

In Fig. 4 there is illustrated a power shaft 31 having a smooth reduced portion 32 providing a stop shoulder 33 and a splined portion 34. A screw shaft 35 is slidably keyed on the splined portion 34 of the power shaft, normally abutting against a ring 36 pressed on the splined portion 34 of the shaft until stopped by the run-out 37 of the splines.

Screw shaft 35 is provided with a threaded portion 38 and a smooth portion 39 on which is normally mounted a nut member 41 having a radial flange 42. A pinion 43 is slidably journaled on the smooth portion 32 of the power shaft for movement into engagement with an engine gear 44. A barrel member 45 is fixed at 46 to the pinion and is keyed to the flange 42 of the nut as indicated at 47, the flange being retained in the barrel by means of a lock ring 48. A re-entry spring 49 is provided between the ring 36 and the end of the barrel 45 for urging the nut 41 into initial engagement with the threads 38, and an anti-drift spring 51 located between the ring 36 and the flange 42 of the nut normally maintains the nut and its associated parts in idle position.

According to the present invention longitudinal movement of the screw shaft 35 away from the engine gear is resisted by an elastically deformable member which is thereby placed in pure axial shear. As here shown this is accomplished by means of an outer barrel member 52 seated on the end of the power shaft 31 in abutting relation with the ends 53 of the splines 34 and clamped there-against by a nut 54 threaded on the end of the power shaft. An elastically deformable ring 55 has sleeves 56 and 57 bonded to its interior and exterior surfaces respectively, and these sleeves are arranged to seat on the end of the screw shaft 35 and the interior of the

barrel 52 against a shoulder 58 on the screw shaft and a shoulder 59 in the barrel respectively.

In the operation of this embodiment of the invention rotation of the power shaft 31 is transmitted to the screw shaft 35 through the splines 34, thereby causing the nut 41 to be threaded along the screw shaft until the pinion 43 is moved into mesh with the engine gear 44 and against the stop shoulder 33. Further rotation of the screw shaft causes it to be moved away from the engine gear, thus applying a shearing force to the ring 55 until the resistance of the ring is built up sufficiently so that the resultant torque transmitted from the nut 41 through the barrel 45 to the pinion causes the pinion to rotate and crank the engine.

It will be appreciated that in all the embodiments of the invention illustrated, the capacity of the yielding connection for the transmission of force is large in comparison with the size of that member inasmuch as all parts of the member are placed simultaneously under stress, and the superficial areas transmitting such stress are large. The fact that in each case, the torque is transmitted through a positive mechanical connection under the control of the yielding shear member, also renders the torque capacity of the device large in comparison to the volume of the yielding member.

Although certain embodiments of the invention have been shown and described in detail, it will be understood that other embodiments are possible, and that changes may be made in the design and arrangement of the parts without departing from the spirit of the invention as defined in the claims appended hereto.

What is claimed is:

1. In an engine starter drive a pair of concentric spaced cylinders, a cylinder of elastically deformable material interiorly and exteriorly connected to said members respectively, torque-responsive means for imparting relative axial movement to said members, and means preventing relative rotation between said members.
2. In an engine starter drive a power shaft, a pinion slidably journaled thereon for engagement with an engine member, means including inter-threaded members for traversing and rotating the pinion, said means including concentric cylindrical members positively connected for rotation in unison with freedom for relative longitudinal movement, and a ring of elastically deformable material having bonded connections interiorly and exteriorly to said concentric members respectively.

JAMES E. BUXTON.
